TUNING PEG FOR MUSICAL INSTRUMENTS

Homer A. Harvey, Batavia, N. Y.

Application May 27, 1940, Serial No. 337,541

2 Claims. (Cl. 84—304)

This invention relates to tuning pegs for musical instruments.

One object of this invention is to provide a remote means to release a string from its seat.

Another object is to provide a slidably mounted spring impelled plunger for preventing frequent adjustment of the peg to retain the desired pitch of the string.

A further object of the invention is to provide a push button control disposed to be operated at the peg handle for removal or replacement of the string.

A further object is to provide apparatus of this character which will be formed of a few strong simple and durable parts, which will be inexpensive to manufacture, and which will not easily get out of order.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming a part of this specification:

Figure 1 is a side elevation of the tuning peg.

Figure 2 is a longitudinal section of the tuning peg showing the plunger normally impelled to abut the string seat, taken on the line 2—2 of Figure 1.

Figure 3 is a longitudinal section of the tuning peg taken on the line 3—3 of Figure 2.

Figure 4 is an end view of the head end of the tuning peg.

Figure 5 is a transverse section taken on the line 5—5 of Figure 3 drawn to large scale.

Referring now to the drawing in which like characters of reference designate similar parts in the various views, a tuning peg 10 for musical instruments is provided with a circular and flattened head 11, whereby the peg 10 may be rotated. The peg is provided with a progressively tapered portion 12 which, when the peg is rotated, is adapted to receive the convolutions of a musical string, not shown. Formed in the tapered portion is a transverse aperture 13 which extends laterally through the tapered portion and to offset laterally from the longitudinal axis of the tapered portion. The aperture 13 is adapted to receive one end of the string and forms a string seat.

The head 11 and tapered portion 12 are provided with a longitudinal bore 14 which com-

municates with a relatively larger longitudinal bore 15. The bore 15 is closed by a plug 16 at the free extremity of the tapered portion 12. The large bore 15 houses a helical compression spring 17 which is secured at one end by a transverse pin 18 which is disposed transversely through the tapered portion 12. The spring expands against a plunger 19 which is slidably mounted within the large bore 15 and impels the plunger 19 toward the string seat 13 disposed 10 at the junction of the bores 14 and 15.

The plunger 19 is provided with serrations 20 on its end remote from the spring 17 for engagement with the musical string. The serrated end 20 is pushed away from the string seat 13 through the medium of a push rod 21 which is extended through the longitudinal bore 14 and is secured in an axial bore in the plunger by a pin 9.

Motion is transmitted to the plunger 19 by pressing on a push button 22 which has a tubular flange 23 to receive the free end of the rod 21. Upon release of the push button 22 the plunger is returned to the string seat by the expansion of the helical spring 17.

A resilient bushing 24 is disposed within a counter bore 25 bored in the bead 11, and the bushing receives the flange 23 of the push button when the push button 22 is pressed outward to move the plunger against the helical spring 17.

In operation the push button 22 is pushed to shift the plunger back from the string seat. Then the musical string is passed through the aperture 13. Then the pressure on the push button is released whereupon the helical spring 17 impels the plunger 19 to engage its serrated end 20 with the string and clamp the string to the string seat while the peg 10 is rotated by the head 11 to wind convolutions of the string on the tapered portion 12.

From the above description it is thought that the construction and operation of the invention will be fully understood without further explanation.

What is claimed is:

1. A tuning device for stringed musical instruments comprising, a peg flattened at one end and tapered progressively at the other end from the flattened end, said flattened and tapered end having a longitudinal bore uniformly enlarged adjacent the small extremity of the tapered end, there being a transverse string receiving aperture at the inner end of the enlarged bore, a plunger slidably mounted in said enlarged bore having a serrated end, an operating rod extending through the longitudinal bore secured to the

serrated end of the plunger, a plug closing the enlarged bore at the tapered extremity of the peg, a compression spring in the enlarged bore disposed against the plug adapted to urge the 5 serrated end of the plunger to engage said string seat, and a push button connected to the plunger for transmitting motion to the plunger to compress said spring and release the plunger from the string seat.

10 2. A tuning peg having a tapered portion provided with a small longitudinal bore terminat-

ing in a relatively larger bore intermediate of its length, said tapered portion having a transverse string receiving aperture at the junction of the small and large bores, a plunger slidably mounted in the large bore having a serrated inner end, a push rod extending through said small bore and secured to the plunger, and a compression spring within the large bore expanding against the plunger to urge the serrated end thereof toward said string receiving aperture. 10
